The ornamental design for the robotic mower, as shown and described.

DESCRIPTION

FIG. 1 is a perspective view of a robotic mower of the present invention;

FIG. 2 is a back view of the robotic mower of FIG. 1;

FIG. 3 is a front view of the robotic mower of FIG. 1;

FIG. 4 is a left side view of the robotic mower of FIG. 1;

FIG. 5 is a right side view of the robotic mower of FIG. 1;

FIG. 6 is a top view of the robotic mower of FIG. 1; and,

FIG. 7 is a bottom view of the robotic mower of FIG. 1.

The broken lines depict portions of the robotic mower that form no part of the claimed design.
